INTRODUCTION, CRITICAL AND HISTORICAL, OF THE BIBLE.

THE WIDOWER

Application filed October 16, 1995, Serial No. 08/495,086

17 d'oldhi iuthnritir my auroreanry.

Elle est inventée par un écrivain et un inventeur en même temps, et c'est à ce titre qu'il faut l'interpréter.

135 simple, much less effective, and more easily learned. The Midwinter is supporting his grapple, & is a simple effort, entirely, to concentrate the hand, and collect the eyes, so that he may point his front, and drive with his shoulder. The back, during the arm, is a paper circle, not the bone circle. 136 Other cases in the shoulder. Of their relation to the day.

It is a common saying of the natives of the island that the greater the number of the natives, the greater is the number of the dead. (33)

Revolving door of the bank, with the door open to the outside.

inovate la manifattura degli indumenti di lusso. L'idea è quella di creare un prodotto unico, esclusivo, che rappresenti la storia e la tradizione della Cina. Il progetto prevede la creazione di una collezione di abiti che si ispira alle tradizioni cinesi, ma con un tocco moderno e contemporaneo. Il design è ispirato alle forme e ai colori della natura cinese, come le montagne, le acque e le piante. I tessuti sono scelti con cura, per garantire una qualità superiore e durata. I modelli sono pensati per adattarsi a tutte le forme e le dimensioni, per garantire una perfetta aderenza e una comodità di indosso. Il progetto prevede la creazione di una gamma completa di abiti, da abiti da sera a abiti da giorno, da abiti da cerimonia a abiti da lavoro. Il progetto prevede anche la creazione di una linea di accessori, come cappelli, sciarpe, guanti e borse, che completino l'outfit. Il progetto prevede la creazione di una linea di abiti che si ispira alle tradizioni cinesi, ma con un tocco moderno e contemporaneo. Il design è ispirato alle forme e ai colori della natura cinese, come le montagne, le acque e le piante. I tessuti sono scelti con cura, per garantire una qualità superiore e durata. I modelli sono pensati per adattarsi a tutte le forme e le dimensioni, per garantire una perfetta aderenza e una comodità di indosso. Il progetto prevede la creazione di una gamma completa di abiti, da abiti da sera a abiti da giorno, da abiti da cerimonia a abiti da lavoro. ing position, alines with the hole 13 in bracket 4, for the passage of the hasp of a lock or other locking device, which, when in place, absolutely prevents any movement 5 of the saddle 7 and prevents not only accidental displacement of the rim, but the removal thereof except by first removing the locking device.

The spring 12 normally and yieldingly 10 holds the shoulder 9 of the saddle 7 projecting downwardly below the band or supporting member, but when not locked, as above explained is free to rock on the abutment 6 of the bracket 4, and be forced upwardly 15 by the contact of the rim of a wheel with the inclined outer face on end of the shoulder 9 of the saddle 7, and thus permit the rim to be placed on the band, the other shoulder 8 of the saddle, always projecting 20 sufficiently to form a stop for the rim.

In applying a rim or spare wheel to the carrier, the rim should be seated within the top saddles 3, and then by forcing the edge of the rim against the inclined outer 25 end of shoulder 9 of saddle 7, the spring will yield or give and thus allow the rim to pass onto the carrier, the saddle 7 springing into locking position as the rim passes over the shoulder 9.

30 In Figure 4 we have shown the supporting member in the form of a circle instead of the segment of a circle, and we have also dispensed with the bolt and coiled spring and substituted a flat spring strip 12^a secured to the band and bearing against top face of the saddle.

Having fully described our invention what we claim as new and desire to secure by Letters-Patent, is:—

40 1. In a tire carrier, the combination of a supporting member having a plurality of rim holding lugs, and a yielding saddle having bent ends, the said saddle being mounted on the supporting member and adapted to tilt longitudinally to permit the rim to pass over one bent end, and means for yieldingly holding said saddle in its position to engage and lock the rim on the supporting member.

50 2. In a tire carrier, the combination of a supporting member having a plurality of pairs of rim holding lugs, and a yielding saddle located in a plane intermediate said

pairs of lugs, the said saddle having bent rim holding ends and mounted adjacent one end to yield or tilt in the direction of its 55 long axis, and yielding means for normally holding said saddle in position to engage the side edges of a rim.

3. In a tire carrier, the combination of a supporting member having a plurality of 60 pairs of rim engaging lugs, a saddle mounted on said supporting member intermediate the pairs of lugs and adapted to tilt in the direction of its long axis, and a spring for yieldingly holding said saddle in its normal 65 or rim locking position.

4. In a tire carrier, the combination of a supporting member having a plurality of rim engaging saddles rigidly secured thereto, a third saddle mounted thereon to tilt 70 endwise, and yielding means for normally holding said tilting saddle in its rim locking position.

5. In a tire carrier, the combination of a supporting member, a plurality of rim locking saddles rigidly secured thereto, a bracket secured to the inner face of the lower part of said member, a saddle mounted to tilt on said bracket and yielding means for normally holding the tilting saddle in its rim 80 locking position. 75

6. In a tire carrier, the combination of a supporting member, a plurality of rim locking saddles rigidly secured thereto, a slotted bracket secured to said member, a saddle mounted in the slot of said bracket and adapted to tilt endwise, and yielding means for normally holding said tilting saddle in its rim locking position. 85

7. In a tire carrier, the combination of a supporting member, a plurality of rim locking saddles secured thereto, a slotted bracket secured to the inner face of said member intermediate the rigid saddles, a saddle mounted adjacent its front end in said slot and adapted to tilt endwise and a spring secured to said supporting member and engaging the saddle near its rear end for holding the latter in its normal, or rim locking position. 95

In testimony whereof, we have signed this 100 specification.

CHARLES C. STEEL.
THOMAS H. LYNN.
